VAPOR JET PUMP

Hans Georg Nöller, Köln-Bayenthal, Germany, assignor to
E. Leybold's Nachfolger, Köln-Bayenthal, Germany, a
firm

Application May 28, 1951, Serial No. 228,555

Claims priority, application Germany June 2, 1950

5 Claims. (Cl. 230—101)

The invention relates to pumps, and more particularly to pumps of the vapor jet type wherein the vapor acts as a propellant removing air or similar gaseous material to produce a vacuum.

It is an object of the present invention to provide pumps of the vapor jet type wherein the stream lines of the propellant vapor jet are prevented from diverging excessively and in fact, are caused to extend substantially parallel to one another.

Another object of this invention is to provide vapor jet type pumps wherein impacts are caused to act at an angle to the jet.

A further object of the invention is to provide vapor jet type pumps wherein the ratio between surface and volume of the jet is materially increased.

Still another object of this invention is to provide pumps of the vapor jet type wherein suction output and compression ratio are materially increased.

Other objects, and the manner in which the same are attained, will become apparent as this specification proceeds.

Existing vapor jet pumps using as the propellant, the vapors of mercury or oil, i. e. of high-molecular substances such as hydrocarbons, chlorinated hydrocarbons, high-molecular esters, silicones, etc., comprise a vapor jet passing from a nozzle into a baffle nozzle to produce a vacuum which is utilized in the removal of gases or vapors contained in vessels or other enclosed spaces connected with the pump. The gases or vapors which as the result of the existence of this vacuum, pass from the vessels or other enclosed spaces into the pump connected therewith and expand in the pump, are carried along continuously by the vapors discharged from the nozzle to pass along, with the said vapors, through the baffle nozzle and into a space wherein the pressure exceeds that prevailing in the pump proper. The walls of the baffle nozzle, more often than not, are cooled whereby to condense the vapor and thus increase the vacuum in the pump. It is common knowledge that vapor jet pumps of the type just described are apt to have a very considerable output.

Tests as well as theoretical investigations, however, have demonstrated that with the vapor jet type pumps proposed and made up to now, the expansion of the propellant vapor jet proceeds in a manner which has an unfavorable influence on the pumping process in that it involves several important drawbacks. In the first place, the stream lines of the propellant vapor jet diverge greatly; the compression impacts occur in a direction substantially parallel to the jet; finally, the surface of the jet is too small by far by comparison with the volume of the jet. In consequence of the drawbacks enumerated above, the suction output and the compression ratio are materially smaller than should be expected on the basis of consideration of energy factors.

The present invention contemplates minimizing the above noted drawbacks of existing vapor jet type pumps, by placing a guide body in the path of the propellant vapor jet. In accordance with the invention, this guide

2

body should answer at least some, and preferably all of the following requirements: It should be a solid body, it should not be cooled and should have a contour such that it results in divergence of the stream lines of the jet being reduced to a minimum; that one or several compression pulses or shock waves (a phenomenon well known in connection with fluids moving at supersonic speeds) act obliquely, or at an angle relative to the jet, and that the ratio of jet surface to jet volume is increased to a maximum in favor of the former if the depth of penetration into the jet of the gas removed by suction is smaller than the diameter of the jet.

In the drawings accompanying this specification and forming part thereof, several embodiments of the invention are illustrated diagrammatically by way of example.

In the drawings,

Fig. 1 is a diagrammatical representation including for comparison purposes, a basic design to which prior art vapor jet type pumps may be reduced;

Fig. 2 is a diagrammatical cross section of one embodiment of the present invention;

Figs. 3 and 4, respectively, are similar diagrammatical representations of two additional embodiments of the invention;

Fig. 5 is a diagram wherein the relation of suction speed to suction pressure is plotted in curves for the pumps of the present invention and prior art pumps, respectively.

Fig. 6 is an axial cross-section of a rotation-symmetrical guide body.

Referring now to the drawing wherein like elements are denoted by identical reference numerals, and first to Fig. 1, this is a diagrammatical representation of a basic design common to prior art vapor jet type pumps. The vapor jet passes from a nozzle D into the baffle nozzle K and conveys the gas to be removed by suction—which owing to the pressure gradient, passes continuously from the vessel to be evacuated (not shown) through the connecting pipe S into the space R—through the baffle nozzle K into the space V where the pressure is higher than in space R. In pumps of this, prior art, type, however, the jets of propellant issuing from the nozzle diverge greatly so as to expand, at high velocity, toward the side walls of the baffle K, whereby the suction output of the pump is materially reduced. This type of pump, manifestly, displays the other serious drawback that the surface of the jet is relatively small by comparison with the jet volume.

Referring now to Fig. 2 and the first embodiment of the present invention illustrated therein, this shows a guide body E arranged below the nozzle D and in the path of the jet issuing therefrom. In the example illustrated, this guide body E has substantially the form of a cone pointing toward the nozzle D, the mantle of the cone being curved so as to present a concave configuration when viewed in cross-section. The jet issuing from the nozzle so as to have its stream lines extend approximately parallel, finds in its path the guide body E the contours of which determine the further course of the jet. In the absence of the guide body, the stream lines of the jet would diverge toward the walls of the baffle K as described above with reference to Fig. 1, this divergence being more pronounced in the outer regions of the jet than in the inner regions. The presence of the guide body, however, results in just the inner stream lines being forced outwardly to a very marked degree, whereas the outer stream lines, which diverge considerably by themselves, are caused to deviate outwardly to the much smaller extent required. Thus the guide body E succeeds in causing substantially all stream lines to be deviated by approximately the same angular amounts, and in caus-

ing any adjacent stream lines to extend in substantially parallel direction.

If the guide body has an outer surface which is strongly curved or bent, such as the mantle of the guide body E which displays sharp bends indicated at A, the guide body, in addition to the effects noted above, originates oblique shock waves which have their origin at such places as the sharp bends shown at A.

Moreover, it is manifest that the guide body E is instrumental in increasing materially the surface of the jet relative to the jet volume, thus improving greatly the ratio between these two factors over the ratio existing in the prior art devices.

Experience has taught that in order to arrive at a satisfactory performance of a vapor jet pump, the angle formed by the stream lines of the jet with the wall of the baffle nozzle, in the vicinity of this wall, must not be excessively large. In order to satisfy this requirement with the embodiment of the invention where the guide body causes the stream lines to deviate materially (e. g. by 90°) from the initial direction of the jet, the inner wall of the pump, in the vicinity of the guide body E, includes a constricted portion Z which surrounds the guide body in spaced relation thereto, to extend substantially parallel to the bent bottom portion U of the guide body. Thus, with the embodiment of the invention shown in Fig. 2, the baffle nozzle K is formed by guide body E and particularly the lower guide portion U thereof, and by the constricted portion Z in the wall of the pump. The guide body is never cooled, but the wall portion surrounding the guide body and forming part of the baffle nozzle may be cooled for the purpose of condensing the propellant vapor.

In place of the concave guide faces of the guide body shown in Fig. 2, guide faces having other configurations may be adopted. Thus, for example, the guide faces might be composed of plane and/or curved portions or segments so as to resemble a polygon. The only essential requirement is that the contours of the guide faces, as a whole, have some concave curvature and include at least one point where a tangential plane passing through this point includes with the initial direction of the vapor jet, an angle exceeding 15°.

According to the embodiment of the invention shown in Fig. 2, the propellant vapor jet has a circular cross section. A guide body according to the invention, however, may be used to equal advantage with pumps where the vapor jet has an annular or rectangular cross section, for example. Figs. 3 and 4 illustrate two further embodiments of the invention where the vapor jets have annular cross sections.

Fig. 3 shows an embodiment of a vapor jet pump having a guide body according to the invention. Oil evaporated in the evaporating vessel O is conveyed through the vapor conduit F, to the nozzle D. Here the oil vapor emerges from an annular slot and in leaving the nozzle D, expands in the form of an annular jet essentially along the lower guide body E and the baffle formed by the cooled wall K. The air to be evacuated which enters the space R through the high vacuum junction S, is carried along by the vapor jet and conveyed through the baffle nozzle, into the rough vacuum space. The guide body E is so shaped that the stream lines of the vapor jet are aligned to extend substantially parallel to one another. For this purpose the vapor jet must be deflected from its original course by nearly 90°, and it is necessary for the cooled wall K to extend again approximately parallel to the deflected vapor jet. The cooled wall, therefore, must extend substantially parallel to the bottom portion U of the guide plane E. The wall K and parts disposed below it are cooled by means of the cooling jacket X through which cooling medium is circulated. To the space V is connected the rough vacuum pipe Y which leads to the rough vacuum pump.

The oil condensed on the cooled walls returns through the return pipe G into the evaporator O.

Fig. 4 shows a further embodiment of a vapor jet pump having a guide body according to the invention. The vapor formed in the heated boiler O enters the annular space D which at its lower extremity is formed as a propelling nozzle. The wall E serving as guide plane strongly deflects the jet from its original course, not outwardly as in the embodiment of Fig. 3, but, on the contrary, inwardly. For this reason the cooled wall K now is disposed in the interior. The cooled wall K is the wall of the hollow body through which cooling water circulates. The air to be evacuated enters the space R through the high vacuum junction S and in consequence of its coming in contact with the vapor jet, diffuses into the propelling jet which conveys it through the annular baffle nozzle formed by the bottom portion U of the guide body and the cooled wall K, into the rough vacuum space V. This space is connected by means of a rough vacuum junction Y, with the rough vacuum pump. The oil condensed on the cooled wall is returned through the return pipe G, to the evaporator O. In this embodiment of the invention again the guide plane E is instrumental in rendering the stream lines substantially parallel.

The precise location of the guide body in the path of the vapor jet, of course, depends upon prevailing requirements. Thus, for example, in certain cases the guide body will not be arranged directly below the nozzle as illustrated in Fig. 2, but will be spaced a considerable distance therefrom.

Fig. 5 illustrates the results of the present invention by a curve denoted as I showing the relation of suction speed to suction pressure, a similar curve denoted as II being shown to illustrate comparable relations for a prior art vapor jet pump. The same propelling nozzle was used in both instances. The numerical values indicated on the suction output curves serve to illustrate the compression ratios at corresponding pressures.

Fig. 6 is an axial cross-section of a rotation-symmetrical guide body E, the section plane being identical with the axis of symmetry. Its border curve includes the straight line U₁, the slightly curved line U₂ and the straight line U₃. The lines U₁, U₂ and U₃ meet at A₁ and A₂, respectively, forming kinks which are known, as is also the curve U₂, to generate in supersonic jet compression impulses.

I wish it to be understood that I do not desire to be limited to the exact details of design, construction and operation shown and described as various modifications well within the scope of the appended claims, may readily suggest themselves to a person skilled in the art.

I claim:

1. A vapor jet pump comprising in combination, a pump casing, a nozzle adapted to emit a vapor jet at supersonic speed, opening into said casing, and a guide body adapted to reduce the divergence of adjacent stream lines of said jet, arranged in the path of the jet issuing from the nozzle and having an effective guide portion so designed that its cross-section taken along the line of the axis of said nozzle has curved contours, the radius of curvature being such that any tangents applied thereto enclose with the axis of said nozzle, an angle of at least 15°, and the cross-section taken at right angles with respect to said nozzle axis has a contour substantially corresponding to the contour of the opening of said nozzle, said pump casing comprising an interior wall portion extending substantially in parallel and in spaced relationship to said guide portion.

2. A vapor jet pump according to claim 1, wherein the cross-section of the guide portion taken along the line of the axis of the nozzle, has contours corresponding to a concave curvature.

3. A vapor jet pump according to claim 1, wherein the cross-section of the guide portion taken along the line of

the axis of the nozzle, has polygonal contours corresponding, on the whole, to an overall concave curvature.

4. A vapor jet pump according to claim 1, wherein the cross-section of the guide portion taken along the line of the axis of the nozzle, has polygonal contours including sharp angles whereby to generate shock waves in the jet impinging thereon.

5. A vapor jet pump according to claim 1, wherein the cross-section of the guide portion taken along the line of the axis of the nozzle, has discontinuously curved contours composed of a plurality of segments of varying radius of curvature whereby to generate shock waves in the jet impinging thereon.
